SHIPPING CONTAINER FOR LABORATORY TUBES AND THE LIKE

Thomas M. Britt, Red Bank, N.J., assignor to Owens-
Illinois, Inc., Toledo, Ohio, a corporation of Ohio

Filed Aug. 13, 1969, Ser. No. 18,660

Term of patent 14 years

Int. Cl. D9—04; D24—99

U.S. Cl. D9—189

FIG. 4

FIG. 5

FIG. 6

FIG. 7

FIG. 8

FIG. 9

FIG. 10

FIG. 11

FIG. 12

FIG. 1 is a top plan view of a shipping container for laboratory tubes and the like, showing my new design;

FIG. 2 is a side elevational view;

FIG. 3 is an end elevational view;

FIG. 4 is a bottom plan view;

FIG. 5 is an enlarged fragmentary cross-sectional view taken along the line 5—5 of FIG. 1;

FIG. 6 is an enlarged fragmentary cross-sectional view taken along the line 6—6 of FIG. 1;

FIG. 7 is a top plan view of a modified form of a shipping container for laboratory tubes and the like, embodying my new design;

FIG. 8 is a side elevational view;

FIG. 9 is an end elevational view;

FIG. 10 is a bottom plan view;

FIG. 11 is an enlarged fragmentary cross-sectional view taken along the line 11—11 of FIG. 7;

FIG. 12 is an enlarged fragmentary cross-sectional view taken along the line 12—12 of FIG. 7;

FIG. 13 is a top plan view of a modified form of a shipping container for laboratory tubes and the like, embodying my new design;

FIG. 14 is a side elevational view;

FIG. 15 is an end elevational view;

FIG. 16 is a bottom plan view;

FIG. 17 is an enlarged fragmentary cross-sectional view taken along the line 17—17 of FIG. 13; and

FIG. 18 is an enlarged fragmentary cross-sectional view taken along the line 18—18 of FIG. 17.

I claim:

The ornamental design for a shipping container for laboratory tubes and the like, substantially as shown.
